UNITED STATES PATENT OFFICE.

JAMES B. ERWIN AND ORLANDO R. ERWIN, OF MILWAUKEE, WISCONSIN.

FIRE-EXTINGUISHING APPARATUS.

1,225,944.

Specification of Letters Patent. Patented May 15, 1917.

Application filed August 31, 1916. Serial No. 117,827.

To all whom it may concern:

Be it known that we, JAMES B. ERWIN and ORLANDO R. ERWIN, citizens of the United States, residing at the city of Milwaukee, 5 county of Milwaukee, and State of Wisconsin, have invented new and useful Improvements in Fire-Extinguishing Apparatus, of which the following is a specification.

Our invention relates to portable fire extinguishing apparatus of the class adapted 10 to be operated by inverting, and especially to that class adapted to generate a large quantity of lingering foam and forcibly discharge the same upon the fire when required.

The primary object of this invention is to provide a very simple removable acid or solution-container of a suitable size and capacity which can be readily inserted into 15 any ordinary standard so-called soda-and-acid type extinguisher, and thereby convert the same into a foam generating extinguisher, merely by substituting the proper chemical solutions, in place of the ordinary 20 soda solution and acid, whereby the ordinary soda-and-acid type extinguishers may not only become highly efficient in extinguishing fires in flammable liquids, oils, 25 greases, etc., but may be readily changed, 30 whereby they are then rendered vastly more efficient on ordinary fires.

In this invention two distinct chemical solutions are normally held separate from each other within a mixing receptacle, and 35 are only allowed to mix when the fire occurs, which mixing is effected by simply inverting the extinguisher, whereby gas is generated which forms the foam with the chemicals, which foam and gas are noxious to 40 the fire.

An important object of this invention is to render all the parts easily removable for inspection, washing and recharging, also the two separate solutions may be quickly prepared direct in their respective compartments without having to mix the same first in separate pails.

Referring to the drawings:

Figure 1 represents an ordinary soda-and-acid-type fire extinguisher, having our improved removable acid-or-solution receptacle inserted centrally, in place of the ordinary type acid bottle and cage, the drawing being largely in central vertical section.

Fig. 2 is a transverse horizontal sectional view, drawn on line 2-2 of Fig. 1.

Fig. 3 is an elevational view in perspective of our improved removable inner solution receptacle, shown removed from the extinguisher shown in Figs. 1 and 2, and

Fig. 4 is a plan view of a bracket shown removed from the extinguisher shown in Fig. 1, said bracket being adapted to receive and retain the lower end of said inner solution receptacle in a central longitudinal position in said extinguisher.

Like parts are identified by similar reference characters in both views.

1 represents the shell of an ordinary soda-and-acid extinguisher of the invertible type, 70 and the same is provided with the usual head 2, securely closing the lower end 3, and the usual collar 4, threaded at 5, is secured to the upper end 6. A wheel cap 7 provided with a threaded annular flange 9 is adapted 75 to engage the threaded collar 4 and tightly close the upper end 6 of the shell 1 as is ordinary construction, whereby a substantially closed tank A is formed which comprises the outer solution receptacle and mixing chamber of our invention. The usual hose 10, provided with nozzle 11, has open communication with the normal upper end 6 of the shell 1, through the coupling nut 14, coupled to an L 12, as is ordinary practice.

As before stated, the ordinary glass acid bottle and cage therefor (not shown in the drawing) are removed and dispensed with, and our improved removable inner solution receptacle B, which is made of a suitable size to fit any ordinary standard extinguisher, is shown installed, Fig. 1, in its operative position within the receptacle A. The said receptacle B, is constructed tubular (of copper, brass, lead or glass), having an outside diameter slightly less than the inside diameter of the collar 4, whereby said receptacle B may be easily slipped through the collar 4 of any standard extinguisher. The said receptacle B is provided at its upper end with a one piece handle or bail 13, 90 preferably rectangular in shape, comprising the horizontal member 30, the two vertical members 31, 31, vertical end members 32, 32 and tapering members 33, 33. The said bail 100 is rigidly connected to the upper end of said receptacle B by means of rivets 18, 18 or the equivalent, rigidly securing said end members 32, 32, to said receptacle. The said bail 13 is formed to nicely and loosely fit within said annular collar 4, having a width 105 slightly less than the inside diameter of said

collar 4, as shown in Figs. 1 and 2. The said receptacle B has a sufficient length so that when standing upon the bottom head 2 of any standard tank A, the bail attached to 5 the upper end thereof will rest loosely within the neck or collar 4, as shown in Figs. 1 and 2.

We also preferably provide at the lower end some steadyng means additional to that 10 of the bail or handle 13 engaging the collar or neck 4, for loosely but removably retaining said secondary receptacle B in a central longitudinal position within said tank A, which may consist of an annular pan- 15 shaped bracket 35, having a dished bottom 36, and an integral annular tapered member 37, extending circumferentially around and a slight distance from the lower end of said receptacle B. The bracket 35 is rigidly fas- 20 tened centrally to the bottom head 2, as shown in Fig. 1, by means of a rivet 38 or the equivalent. The receptacle B is closed at its lower end 21 by means of a head 20 secured leak-proof to the tube 16 in any 25 suitable manner.

The said receptacle B is provided with a loosely fitting lead or glass stopple 26 which is adapted to rest upon and normally close the upper end of said receptacle B. 30 The stopple 26 is provided with an annular groove 28, upon its lower face, adapted to loosely fit over the upper open end of said tube 16, whereby any preliminary mixing of the two separate solutions, due to any 35 unusual shaking of the extinguisher, is avoided.

To charge our improved extinguisher (three gallon size) the wheel cap 7 is first 40 unscrewed and removed in the usual way. Then the inner receptacle B, together with stopple 26, is slipped out through the neck 4 when the two receptacles A and B may be charged as follows:—

45 Place in receptacle A.

1st—Cold water— $2\frac{1}{2}$ gallons
2nd—Sodium bicarbonate—22 ounces
3rd—Powdered soap bark—2.3 ounces
50 And stir thoroughly until these chemicals are dissolved.

Place in removed receptacle B.

1st—Cold water—3 pints
55 2nd—Aluminium sulfate—3 pounds

NOTE—Add the aluminium sulfate slowly to the water as you stir until all is dissolved.

Now place the loose stopple 26 back upon its seat on the receptacle B, and slip the receptacle uprightly into the tank A through collar 4. The lower end of the receptacle B should be inserted centrally within the bracket 37 therefor, which is located on the lower head of tank A. The wheel cap 7 is 65 then screwed back tightly in place upon its

collar 4 when the extinguisher is charged and ready for a fire. To discharge the extinguisher the same has simply to be inverted or reversed so that the wheel cap 7 stands upon the floor. The stopple 26 then falls from its seat 24, and the two solutions rapidly commingle to form carbon-dioxide gas, which forms the foam with the chemicals which is forcibly discharged through the hose 10 and nozzle 11, in the form of millions of minute bubbles of lingering foam. A three gallon extinguisher constructed on this principle and employing the above chemicals generates from twenty-five (25) to thirty (30) gallons of foam 80 which is thrown through a quarter of an inch nozzle a distance of from thirty-five to forty feet for a period of one minute, and will extinguish a tank of burning gasoline having a surface area of thirty square 85 feet.

Having thus described our invention what we claim as new and desire to secure by Letters Patent, is:—

1. The combination of an ordinary standard tip-over fire extinguisher tank of the soda-and-acid type, an elongated cylindrical inner solution receptacle, removably installed therein, through the usual top collar-neck of said extinguisher tank, a bail, 90 rigidly connected to the upper end of said inner receptacle, said bail fitting loosely in the collar of said extinguisher tank, for loosely retaining the upper discharge end of said inner receptacle in a central longitudinal position in said extinguisher tank, and a gravity opening stopple seating unattached upon and closing the upper end of said inner receptacle.

2. A fire extinguisher, comprising a substantially closed tubular outer receptacle, an elongated tubular inner receptacle loosely and removably installed therein in a longitudinal position, said receptacles having openings at corresponding ends, a collar attached to said outer receptacle at the opening thereof and having a neck rigidly fastened thereto, an outer cover for said neck, means for securely holding said cover upon said neck, a bail, rigidly connected to the discharge end of said inner receptacle and said bail fitting loosely in the collar of said outer receptacle, an inner stopple seating upon but unattached to the discharge end of said inner receptacle, together with means rigidly affixed to the inside wall of said outer receptacle for loosely and removably supporting and retaining the lower end of said inner receptacle in a longitudinal position within said exterior receptacle.

3. In a fire extinguisher of the described class, the combination of an exterior receptacle provided at its upper end with a discharge opening and a contracted neck, and at its lower end with an outwardly

and upwardly tapering bracket adapted to surround and removably retain the lower end of an inner receptacle in place in said exterior receptacle, an inner receptacle provided at its upper end with a loosely fitting stopple and a bail, said inner receptacle being of uniform diameter throughout its length, said bail being adapted to removably fit the contracted neck of said inclosing receptacle, while it retains said inner receptacle in place and facilitates removing the same from said outer receptacle.

In testimony whereof we affix our signatures in the presence of two witnesses.

JAMES B. ERWIN.
